UNITED STATES PATENT OFFICE.

HENRY J. WARREN AND CARL NORDELL, OF STAMFORD, CONNECTICUT,
ASSIGNORS TO THE STAMFORD FOUNDRY COMPANY, OF SAME PLACE.

FIRE-BOX FOR STOVES, RANGES, &c.

SPECIFICATION forming part of Letters Patent No. 643,430, dated February 13, 1900.

Application filed July 11, 1898. Serial No. 685,613. (No model.)

To all whom it may concern:

Be it known that we, HENRY J. WARREN and CARL NORDELL, of Stamford, in the county of Fairfield and State of Connecticut, have invented certain new and useful Improvements 5 in Fire-Boxes for Stoves, Ranges, &c., of which the following is a full, clear, and exact description.

This invention relates to fire-boxes, but 10 more particularly to fire-boxes for ranges and cooking-stoves.

The primary object of the invention is to provide a simple and efficient sectional frame whereby the usual fire-bricks may be protected 15 and retained in position in the fire-box and in case of injury to the frame one or more parts thereof may be removed and repaired or other pieces or sections substituted therefor with very little trouble, thereby dispensing 20 with the usual brick-rest or grate-frame and overcoming many of the objectionable features incident to devices of this character as ordinarily constructed.

Other objects are to provide means which 25 will permit various forms of grate-bars to be employed, to provide means which will allow proper expansion of the parts, and to provide a sectional frame which is adapted for use in connection with various forms of stoves, 30 ranges, &c.

The invention will be hereinafter more particularly described with reference to the accompanying drawings, which form a part of this specification, and then pointed out in the 35 claims at the end of the description.

In the drawings, wherein similar numerals of reference indicate similar parts, Figure 1 is a vertical sectional view, partly in elevation, of one form of range with the invention applied thereto, the section being taken on the line I I of Fig. 2. Fig. 2 is a sectional plan, on a larger scale, partly broken away, taken on the line II II of Fig. 1. Fig. 3 is a fragmentary vertical section through the fire-box, 45 taken on the line III III of Fig. 2, the pitch-line only of the gears connecting the shafts of the grate-sections being shown. Fig. 4 is a fragmentary vertical section taken on the line IV IV of Fig. 2. Fig. 5 is a fragmentary sectional plan taken on the line V V of Fig. 4; and Fig. 6 is a detail perspective view, partly

broken away, of a portion of the sectional frame.

The casing 10 may support the usual cover or top for cooking utensils and is provided 55 with a suitable fire-box 10^a. This fire-box has suitable lugs 11, adapted to support the bricks 12, which have their lower ends rabbeted, so as to fit upon and between said lugs. A plate 13 may have its upper end secured to the casing 10 and its lower end made angular to support the end brick or bricks 14. The features thus far described, either in part or as an entirety, may be of any preferred form or construction. 60

For the purpose of retaining the fire-bricks in their proper position and to prevent injury to the lower edges thereof by the coal and to permit the parts to be readily removed or repaired a sectional frame, as 15, is preferably arranged beneath the bricks. As shown, this frame has an end section or bar 15^a, provided with a flange 16, which is adapted to fit in a recessed edge of the brick or bricks above the same and has its outer ends rab- 65 beted or recessed, as at 17, so as to be removably engaged by the sections or bars 18. The sections 18 have flanges 19, similar to the flange 16 of the end section, which fit recesses in the lower edges of the bricks and have 70 their ends 20 L-shaped or otherwise formed and adapted to rest upon the base-plates 21 above the same and to be rigidly held thereto. The base-plates of the bracket, Figs. 2, 3, and 6, have holes or apertures therein, through which pass the 75 screw-bolts 23, the latter serving to rigidly hold the bracket to slotted ears or lugs 24 on the fire-box casing. This bracket has the standards 25, which support the guard-bar 26 and serve to limit the outward movement of 80 the ends of the side sections 18. The guard-bar 26 abuts against a pendent flange 26^a on the plate 13, which latter, together with the flange 16 thereon, serves to protect the gears 27 from the heat as much as possible, the gears 85 being rigidly held to the shafts 28 and 28^a, one of which, as 28, has a polygonal end to permit it to be turned to rotate the shafts in unison in the usual manner. The shafts of the grates have one of their ends supported 90 in a hanger or spacing-bar 29, so as to pass beneath the guard-bar 26 of the bracket 22,

said hanger serving as a spacing and locking bar and having apertured ends, through which pass pins or bolts 30, which engage apertures in the base-plates 21 of the bracket to 5 movably hold the hanger to said bracket, the ends of the hanger being adapted to engage the inner edges of the side sections, so as to rigidly and removably hold the same apart. By this means the parts are interlocked, and 10 the end and side sections of the frame are locked together and to the bracket, though instead of the bracket being fastened it may be arranged in any suitable manner and the end and side sections of the frame made to 15 interlock with each other and be held in the fire-box, as desired.

The shafts 28 and 28^a have the hubs 30^a of the gears 27 secured thereto and have one of their ends supported in the hanger or locking-bar 29 and their other ends supported in the hanger 31, which is secured to the casing by the bolts 32. The hanger 29, as well as the hanger 31, may have an intermediate socket 33 to permit either single or duplex grates to be employed. These features are only referred to generally herein and form subject-matter for a divisional application filed March 10, 1899, Serial No. 708,592.

The invention will be readily understood 30 from the foregoing description when taken in connection with the accompanying drawings.

If the frame or any part thereof is to be removed, the pins 30 are disengaged from 35 the base-plates of the bracket 22 and the hanger 29 forced outwardly through the opening in the fire-box casing. This releases the ends 20 of the side sections or bars 18 and will permit the grate-bar shafts to be 40 lowered in the hanger 31 or removed. The ends 20 of the sections 18 may be forced inwardly, which will permit them to be withdrawn through the opening in the casing and will leave the end section or bar 15^a free 45 to be withdrawn, if desired. When the side sections 18 are removed, the bracket 22 may be removed by releasing the bolts 23. The reverse of the operation just described takes place when the parts are to be placed in position in the fire-box.

From the foregoing it will be seen that the parts of the frame may be readily removed for repairs or for other purposes, that the bricks are retained in position and their lower 55 edges protected, and that provision is made for the proper expansion of the parts.

When the corners of the casing are rounding, the side sections 18, as well as the base-plates 21 of the bracket, may be cut away to 60 conform to the contour of the casing or otherwise made to fit therein, and where it is found desirable some of the parts may be differently constructed or some of the parts dispensed with and others substituted therefor without 65 departing from the spirit of our invention.

Having thus described our invention, we claim as new and desire to secure by Letters Patent—

1. In a device of the character described, a frame comprising interlocking end and side sections adapted to engage the lower edges of the fire-bricks to retain the same in position, and a removable hanger and spacing-bar connecting one end of the side sections and holding the same in fixed relative positions, substantially as described. 75

2. A frame for fire-boxes, comprising an end bar or section provided with rabbeted ends, side sections fitting the rabbeted ends of the end section, a bracket forming a support for one end of the side sections, and means for spacing the side sections apart and locking them to the bracket, substantially as described. 80

3. A frame for fire-boxes, comprising an end section, interlocking side sections or bars removably engaging the end section, a bracket forming a support for one end of the side sections, and a hanger forming a locking-bar to rigidly lock the sections together and to the bracket, substantially as described. 85

4. A frame for fire-boxes, comprising an end section or bar provided with rabbeted ends, side sections or bars fitting the rabbeted ends of the end section, the said sections having flanges adapted to engage the lower edges of the fire-bricks to retain the same in position and prevent injury thereto, a bracket forming a support for one end of the side sections, and a hanger forming a locking-bar to removably lock the sections together and to the bracket, substantially as described. 95 100

5. In a device of the character described, the combination with a fire-box casing having lugs thereon to support the fire-bricks, 105 and an end plate having a pendent flange and forming a support for the brick or bricks at one end of the fire-box, of a sectional frame adapted to retain the bricks on the lugs and prevent injury to the lower edges thereof, 110 one member of said frame having a guard-bar abutting against the pendent flange of the plate, and means for removably locking the sections of the frame together, substantially as described. 115

6. In a device of the character described, the combination with a fire-box casing having means for supporting the fire-bricks therein, of an interlocking sectional frame adapted to retain the bricks on their supports and prevent injury to the lower edges thereof, and a removable hanger serving as a locking-bar and forming a portion of the frame, substantially as described. 120
